UNITED STATES PATENT OFFICE.

FLETCHER CHADWICK, OF ROCHDALE, ENGLAND.

FRAME FOR DOUBLING YARNS.

1,400,026.

Specification of Letters Patent. Patented Dec. 13, 1921.

Application filed July 9, 1920. Serial No. 395,035.

(GRANTED UNDER THE PROVISIONS OF THE ACT OF MARCH 3, 1921, 41 STAT. L., 1313.)

To all whom it may concern:

Be it known that I, FLETCHER CHADWICK, a subject of the King of Great Britain, residing at Fieldhouse Mill, Rochdale, in the county of Lancaster, England, have invented new and useful Improvements in Frames for Doubling Yarns, (for which I have made application in Great Britain April 20, 1917, Patent No. 106,978,) of 10 which the following is a specification.

My invention relates to improvements in frames for doubling yarns from warpers' beams.

It is well known that doubling or twisting from one or more warpers' beams has been carried on previously for preparing yarns in the manufacture of heavy counts for twines, netting, ducks, and other coarse or heavy fabrics.

15 In such cases it has been customary to support the warper's beam, or each beam, in a creel upon a driven drum and to deliver the yarns from the warper's beam as it is rotated by surface contact with its driving drum but this method has been unsatisfactory because the threads as delivered from the beam are uneven in tension, thereby causing more or less corkscrewed yarn and, further, the dividing and distribution of 25 the threads to the spindles are the cause of much unequal tension owing to the spindles being disposed over a wider area than the width of the warper's beam.

To overcome these defects it has been proposed to mount the warpers' beams or beam upon stands and pull off the yarn by means of top and bottom lines of drawing rollers but this method also has encountered difficulties in the distribution of the threads 40 and in limiting the doubling to one side of the frame owing to the necessity of delivering the yarn in as near a straight line as possible to the spindle.

According to my present invention I propose to dispense with driving drums and to mount the warper's beam or beams upon a suitable creel framing allowing the beam or beams to be rotated only by pulling the yarn off by means of the usual lines of 45 top and bottom drawing rollers employed in certain doubling frames and I distribute and guide the threads to the nip of the

5 drawing rollers in the following novel manner:—

The threads are drawn off vertically in 55 tape form from the beam or beams and distributed diagonally to the drawing rollers and thence to the spindles by means of suitable guides and carriers over the wider distance occupied by the spindles. 60

The first set of guides are placed near and preferably below the beam in order to assemble the required number of threads for each spindle in tape form and adjustable 65 carriers are arranged to guide and carry the tapes obliquely to their respective spindles beyond the width of the beam.

I illustrate my improved beam doubling frame in the accompanying sheet of dia- 70 grammatic drawings in which:—

Figures 1 and 1^a are a front or back elevation. Figs. 2 and 2^a are a plan and Fig. 3 is an end view of so much of the frame as it is necessary to show for the purpose of 75 explaining my invention.

Figs. 4 and 5 are detail views of a suitable form of thread guides, Fig. 4 showing the guides used on the left and Fig. 5 the guides used on the right hand side of the 80 machine.

In these views, *a*, *a'* designate the two warpers' beams, *b* the creel in which they are supported: *c* the threads, *d* a rail, preferably of V shape as shown or crescent shaped and carrying two series of thread 85 guides *e* placed right and left hand as shown in the detail views, Figs. 4 and 5; *f*, *f'* adjustable rails each carrying a series of intermediate thread guides or carriers; *g* thread guides for guiding and delivering the ends 90 to the driven drawing rollers *h* which are supported and driven in the known manner; *i* thread guides beyond the drawing rollers; *j* the travelers; and *k* the bobbins on which the doubled and twisted ends are 95 wound in the usual way.

Beginning at the middle of the warper's beam *a* or *a'* the threads for each spindle, two or more ends as the case may be, are drawn off in tape form from each warper's beam and taken vertically downward through the first of say the right series of thread guides *e* and then diagonally to the first thread guide *g* of the right hand series 100

through the drawing rollers *h*, through the corresponding thread guide *i* and thence to the traveler *j* by which it is twisted and wound upon its bobbin *k* or equivalent part.

5 In like manner each succeeding group of ends is drawn off the warper's beam and led through the successive thread guides in tape form and in proper order, the tape form being maintained by the configuration and 10 arrangement of the guides.

As will be seen on referring to Fig. 4, the guide *e* is so formed and placed as to give a double bearing for the threads as they are drawn vertically downward through the 15 guide *e* and away to the right and in like manner the right hand series of guides *g* and *i* are similarly or equivalently formed and placed so as to maintain each group of ends flat and prevent them coiling up or 20 corkscrewing.

After, say, eight or nine spindles from the center on the right hand side have been fed, the angle for the next group of ends becomes too wide for the threads to be led 25 directly to the drawing rollers without an intermediate support and therefore the remaining series of threads on the right hand side as they leave their guides *e* are passed over round pins or equivalent guides or carriers mounted on the adjustable rail *f* before 30 being taken to the guides *g* and through the drawing rollers *h*.

The threads for the left hand series of 35 guides *e* are selected from the middle of the warper's beam and led through guides to the spindles in like manner, the thread guides on the left hand side of the frame being set as indicated in Fig. 5 so as to give a double bearing for the ends and maintain 40 them in tape form as already specified.

It will be readily understood that the machines may have a single warper's beam and

any suitable number of spindles on one side only instead of two beams and spindles on both sides as shown; that fliers instead of 45 rings and travelers may be employed for doubling and twisting the threads; and that any suitable type of thread guide may be employed provided that each group of ends is maintained in tape form and prevented 50 from coiling up on its way from the warper's beam to the spindle.

I also wish it to be understood that I prefer to apply any suitable form of brake to each warper's beam in order to prevent 55 it over running as the threads are drawn off.

What I claim as my invention and desire to secure by Letters Patent is:—

1. The combination with a warper's beam 60 doubling frame, of a plurality of spindles, drawing rollers parallel with said beam, means for drawing off groups of threads vertically in tape form from said beam, and means for distributing said groups diagonally to the drawing rollers and thence to 65 the spindles over the wider distance occupied by the spindles, while maintaining the groups in tape form.

2. In a doubling frame, in combination a warper's beam; a line of driven drawing 70 rollers parallel with said beam; a series of spindles extending beyond the width of the beam, and adjustable thread guides between said beam and spindles to distribute diagonally to its respective spindle each group of 75 threads drawn in tape form from the beam substantially as herein set forth.

In testimony whereof I have signed my name to this specification.

FLETCHER CHADWICK.
